UNITED STATES PATENT OFFICE.

FREDERICK MAX PORITZ, OF NEW YORK, N. Y., ASSIGNOR TO STAR CHANDELIER COMPANY, INC., OF NEW YORK, N. Y., A CORPORATION OF NEW YORK.

DESIGN FOR A TWO-LIGHT BODY HOLDER FOR A CHANDELIER.

Application filed July 19, 1924. Serial No. 10,186. Term of patent 3½ years.

To all whom it may concern:

Be it known that I, FREDERICK MAX PORITZ, a citizen of Germany, residing in New York, in the county of New York and State of New York, have invented a new, original, and ornamental Design for a Two-Light Body Holder for a Chandelier, of which the following is a specification, reference being had to the accompanying drawing, forming part thereof.

Figure 1 shows a side elevation of my new design for a two light body holder for a chandelier.

Figure 2 shows a bottom plan view of a two light body holder for a chandelier, and I claim:—

The ornamental design for a two light body holder for a chandelier as shown.

FREDERICK MAX PORITZ.
